UNITED STATES PATENT OFFICE.

JAMES D. BENBOW, OF AURORA, ILLINOIS, ASSIGNOR TO WESTERN WHEELED SCRAPER COMPANY, OF AURORA, ILLINOIS, A CORPORATION OF ILLINOIS.

OPERATING MECHANISM FOR DUMP CARS.

Application filed December 2, 1918. Serial No. 265,001.

To all whom it may concern:

Be it known that I, JAMES D. BENBOW, a citizen of the United States, and a resident of Aurora, in the county of Kane and State 5 of Illinois, have invented certain new and useful Improvements in Operating Mechanism for Dump Cars, of which the following is a specification, reference being had to the accompanying drawings.

10 My invention relates to dump cars in which the car bed is dumped and righted by compressed air, and has particularly to do with such dump cars in which the valve mechanism by which the admission of compressed air to the cylinder or cylinders of the car and its exhaustion therefrom is controlled is operated independently of the air pressure in the chamber or duct through which compressed air is supplied to the 15 operating cylinder of the car. Operating mechanisms of this type are designed for use in systems comprising a main air supply, such as a train pipe carrying compressed air supplied from the locomotive, 20 and an auxiliary air supply contained in a series of reservoirs carried by the several cars of the train, which reservoirs are charged from the train pipe. The air by which the operating cylinders of any given 25 car are operated is taken from the reservoir carried by that car, the admission of such air to the operating cylinders being ordinarily controlled by valve mechanism actuated to admit the air to such operating cylinders or to exhaust it therefrom by compressed air received directly from the main supply, although in some cases provision is also made for operating such valve mechanism by air taken from one of the reservoirs. 30

The object of my present invention is to provide certain improvements in operating systems of the type described, and particularly in the valve mechanism thereof, as will fully appear from the following description of the embodiment thereof illustrated in the accompanying drawings. What I regard as new is set forth in the 35 claims.

40 In the accompanying drawings:

Fig. 1 is a perspective view illustrating the principal parts of the dumping mechanism of a car, having my improved valve mechanism incorporated therein;

45 Fig. 2 is a view principally in section, il-

lustrating my improved valve and its connections, the valve being shown in its normal position;

Fig. 3 is a sectional view of my improved valve mechanism illustrating the valve in 50 position to admit compressed air to the operating cylinder of the car; and

Fig. 4 is a view principally in section, showing the valve mechanism illustrated in Figs. 2-3 combined and cooperating with a 55 cut-off valve arranged to be actuated by the piston in the operating cylinder when it approaches the end of its operating stroke.

Referring to the drawings, 5 indicates the train pipe which is supplied with compressed air from the locomotive. As illustrated in Fig. 1, the intermediate portion of the train pipe extends across the car so that its opposite end portions are at opposite 60 sides of the car. The ends of the train pipe 65 are provided with couplings 6 for connecting together the train pipes of adjoining cars in the train. Cut-off valves 7 are also provided at the end portions of the train pipe, as shown in said figure. 8 indicates 70 the air reservoir hereinbefore referred to, which is suitably mounted on the underbody of the car, and is adapted to receive air from the train pipe 5 through a branch pipe 9, which is connected with the train 75 pipe 5 as shown in Fig. 1. The branch pipe 80 9 is provided with a check valve 10 for preventing back-flow of air from the reservoir 8 through the pipe 9 to the train pipe 5. Said branch pipe is also provided at opposite 85 sides of the check valve 10 with cut-off 90 valves 11-12, the purpose of which will be hereinafter explained. 13-14 indicate auxiliary train pipes, one of which is provided 95 at each side of the car, said pipes being provided at their ends with couplings 15-16, respectively, and with cut-off valves 17-18, respectively. Thus the several auxiliary train pipes of the cars of the train may be 100 connected in series, or the auxiliary train pipes of any car may be cut off from the others by closing the valves 17 and 18 of such car. 19 indicates a pipe which leads from the branch pipe 9 between the check 105 valve 10 and the cut-off valve 12, as shown in Fig. 1, and is connected with both auxiliary train pipes 13-14. As shown in said figure, the pipe 19 is connected with the auxiliary train pipe 13 by a pipe 20 provided with a valve 21 similar to a stop and waste 110

cock in that when open it admits air from the pipe 9 through pipe 20 to the auxiliary pipe 13, and when closed it cuts off the pipe 13 from the pipe 19 and permits the air 5 in the pipe 13 to exhaust into the atmosphere. In the construction shown, the valve 20 is operated by a lever 22 carried by a rod 23 which is an extension of the valve plug. Similarly the pipe 19 is connected with the 10 auxiliary train pipe 14 by a pipe 24 provided with a valve 25 similar to the valve 21, and arranged to be operated by a lever 26 carried by a rod 27. From the foregoing description, it will be apparent that when 15 the valves 21 and 25 are closed and the valves 11 and 12 are open, compressed air will be admitted to the reservoir 8 from the train pipe 5, and in like manner all the reservoirs of the several cars may be charged 20 from the train pipe. It will also be seen that the auxiliary train pipe 13 may be supplied with compressed air either directly from the train pipe 5 or from the reservoir 8, since by closing valve 12 and opening valve 21, 25 compressed air will flow from pipe 5 through branch pipe 9 to pipe 19, and thence through pipe 20 to pipe 13, or by closing valve 11 and opening valve 21, compressed air will flow from the reservoir 8 through pipes 9, 30 19, and 20 to pipe 13. By keeping valve 21 closed, and opening valve 25, the auxiliary train pipe 14 may be supplied with compressed air from either source in the same way.

35 28—29 indicate the two operating cylinders of the car which, as shown in Fig. 1, are placed at opposite sides of the car near the longitudinal center thereof. As illustrated in Figs. 2 and 4, these cylinders are 40 provided with pistons or plungers 30, the rods 31 of which extend up through the upper head 32 of the cylinder. These piston rods are preferably tubular, and are operatively connected in any approved way with 45 the car bed so that when the piston is actuated by the admission of compressed air to the cylinder the car bed will be dumped or righted, as the case may be. The construction of such connecting devices is not shown, 50 as the improvements which form the subject-matter of this application may be employed in connection with a variety of such connecting devices, and the latter form no part thereof.

55 Referring now more particularly to Figs. 2-3, which illustrate the automatic valve mechanism by which the admission of compressed air to and its exhaustion from the cylinders 28—29 from the reservoir 8 is 60 controlled, 33 indicates the casing of the valve, which comprises a main valve chamber 34 which is in the form of an elongated cylinder, an auxiliary chamber 35 adjacent to one end of the main chamber 34, and a 65 drip chamber 36 below the auxiliary chamber

70 35. As shown in Fig. 2, the auxiliary chamber 35 is of considerably greater diameter than the main chamber 34, and has mounted therein a piston 37, the stem 38 of which is adapted to project into the adjacent end of the main chamber 34. The piston 37 is provided with a cup washer 39, of leather or other suitable material, which fits closely in the bore of the chamber 35. 40 indicates a port which affords communication 75 between the drip chamber 36 and the auxiliary chamber 35. 41 indicates a laterally disposed inlet duct through which air may be admitted to the drip chamber 36 from a pipe 42 which connects with one or the other of the auxiliary train pipes 13—14. 43 indicates a deflector in the drip chamber 36 opposite the inner end of the duct 41 for promoting condensation of moisture. 44 indicates a plug closing the bottom of the drip 80 chamber 36. It will be apparent from the foregoing description that compressed air admitted to the drip chamber 36 will pass up through port 40 into the auxiliary chamber 35, thereby forcing the piston up in said 85 chamber. When the pressure in the drip chamber 36 is released, the piston 37 is returned to its normal position, shown in Fig. 2, by the pressure in the main chamber 34 above the piston therein, as hereinafter described, assisted, if desired, by a spring 45 interposed between said piston and the upper end of the auxiliary chamber 35. (It 90 will be understood that the terms "up" and "down" as herein used are relative only.) 100 The upper end portion of the main valve chamber 34 is provided with an inlet duct 46 which is connected by a pipe 47 with the reservoir 8 so that compressed air is admitted directly from the reservoir 8 to said 105 duct. 48 indicates a cylindrical bushing in the main valve chamber 34, which bushing is provided with three series of ports. The uppermost series 49 is arranged opposite an annular channel 50 which connects with the 110 inlet duct 46 through a laterally-disposed duct 51. The lowermost series of ports 52 lies opposite a series of exhaust ports 53 which connect with the main valve chamber 34 with the auxiliary chamber 35. An intermediate series of ports 54 registers with an annular groove 55, which connects with an 115 outlet duct 56 at one side of the valve casting 33, said duct having connected therewith a pipe 57 which leads to a duct 58 in the lower head 59 of the cylinder 28. 60 indicates a cylindrical piston or slide valve, the intermediate portion of which is of reduced diameter, and which carries adjacent to its 120 ends cup washers 61—62, which bear closely in the bushing 48. These washers are spaced apart a sufficient distance so that by moving the piston 60 longitudinally in the main valve chamber 34 it will operate to connect the ports 49 and 54, or the ports 52 and 54. 130

When the ports 49 and 54 are connected, compressed air admitted to the upper portion of the main valve chamber may pass through the ducts 49 and around the intermediate portion of the piston 60 to the ports 54, and then through duct 56 to the operating cylinder 28 or 29, as the case may be. This position is illustrated in Fig. 3. When the parts are in the position shown in Fig. 10 2, the ports 54 are connected with the ports 52, and the compressed air in the operating cylinder may flow through pipe 57 and duct 56 to the valve chamber 34 and be discharged into the auxiliary chamber 35 through ports 15 53. The upper portion of the auxiliary chamber is provided with exhaust ports 63, through which air in the auxiliary chamber 35 above the piston 37 is exhausted to the atmosphere. 64 indicates a bolt which connects the piston 60 with the piston 37 so that they move in unison. It will be observed that the upper end of the piston 60 is exposed to the pressure in the main chamber 34, so that said pressure, which may be 20 assisted, if desired, by using the spring 45, operates normally to restore the parts to the 25 position shown in Fig. 2, and thereby exhaust the air from the operating cylinder.

The operation of the mechanism thus far 30 described is as follows: The parts being in the position shown in Fig. 2, when it is desired to operate the piston in one of the operating cylinders, as 28, the valve 21 is 35 opened by means of the lever 22, thereby admitting compressed air to the auxiliary train pipe 13 either from the main train pipe 5 or from the reservoir 8, depending upon the position of the valves 11-12, as hereinbefore explained. The compressed air admitted to the pipe 13 enters the drip chamber 36 and passes through port 40 into the auxiliary chamber 35 below the piston 37, forcing said piston up and moving the main valve piston 60 up to the position shown in 40 Fig. 3, and thereby connecting the inlet duct 46 of the main valve chamber with the outlet duct 56 thereof. This admits compressed air to the operating cylinder 28, and forces its piston up, thereby dumping the car bed or restoring it to its operative position according to circumstances. If the valves 17 at the opposite ends of the auxiliary train pipe 13 are closed on the car whose valve 21 is open, only the operating 45 cylinder of that car will receive compressed air, but if the valves 17 are open, all cars in communication therewith will be similarly operated. When the valve 21 is closed, the pressure in the lower portion of the auxiliary valve chamber 35 will be released as the air in the pipe 13 will be exhausted through the valve 21. The pressure in the main chamber 34 will thereupon operate to move the piston 37 down, thereby moving 50 the piston 60 into the position shown in Fig.

2, which will connect the duct 56 and the operating cylinder with the upper portion of the auxiliary chamber 35, which, as has been explained, communicates with the atmosphere through exhaust ports 63. Thus 70 the air in the operating cylinder 28 will be permitted to exhaust into the atmosphere. While the pressure is constantly maintained in the upper portion of the main valve chamber 34, this does not prevent the operation of the pistons 37 and 60 in the manner described, owing to the larger diameter of the piston 37. 75

In Fig. 4 I have illustrated the valve mechanism above described, combined and cooperating with means for automatically cutting off the further admission of compressed air to the operating cylinder when the piston thereof approaches the limit of its operating stroke. In the construction illustrated in said figure, the port 46 is extended, as shown at 46^a, and leads to an annular groove 65 which surrounds a cut-off chamber 66, in which is mounted a cut-off valve 67 movable in said cut-off chamber into position either to connect said cut-off chamber with the duct 46^a or to cut them off from each other. Preferably said cut-off chamber is provided with a bushing 68 having ports 69 which register with the groove 65, and the valve 67 is provided with a pair of cup washers 70-71 spaced apart, as shown in Fig. 4. The upper portion of the cut-off chamber 66 connects by a duct 72 with the pipe 47, and when the cut-off valve 67 is in its uppermost position the cup washer 70 overlies the ports 69 and disconnects the duct 72 from the duct 46^a. When the cut-off valve 67 is in its lowermost position compressed air may flow from duct 72 through ports 69 to duct 46^a, and into the main valve chamber. 100 105 110

The cut-off valve 67 rests upon the upper end of a plunger 73 which is fitted in a suitable bearing in the upper head 32 of the operating cylinder and extends down a short distance thereinto, as shown in Fig. 4, in position to intercept the piston 30 when it approaches the upper limit of its operating stroke. Thus the piston 30 operates to raise the plunger 73 and lift the cut-off valve 67 into position to close the ports 69. The cup washer 71 is constantly interposed between the ports 69 and the opening in which the plunger 73 is fitted, and consequently prevents leakage of compressed air into the operating cylinder above the piston 30 therein. By this construction, when the piston 30 reaches the limit of its operating stroke, the further admission of compressed air to the operating cylinder is cut off and remains cut-off until the pressure in the operating cylinder below the piston is released, whereupon the piston 30 descends and the cut-off valve 67 is restored to 115 120 125 130

its operative position, shown in Fig. 4, by the pressure of the air admitted through pipe 47 from the reservoir 8. I have used the terms "main" and "auxiliary" in connection with the valve chambers merely for convenience of description.

What I claim as my invention and desire to secure by Letters Patent, is:—

1. In an operating mechanism for dump cars, the combination with means for supplying compressed air, and an operating cylinder, of a valve interposed between said air supplying means and said cylinder, said valve comprising a main valve chamber, an inlet duct leading to one end portion thereof, an auxiliary chamber communicating with the opposite end of said main chamber, a passage communicating intermediately with said main chamber and connected with said cylinder, an exhaust port leading from said main chamber into said auxiliary chamber, a second exhaust port leading out of said auxiliary chamber, a valve movable in said main chamber to connect said passage either with said inlet duct or with said first mentioned exhaust port, and means actuated by the admission of compressed air to said auxiliary chamber for moving said valve to connect said inlet with said passage.

2. In an operating mechanism for dump cars, the combination with means for supplying compressed air, and an operating cylinder, of a valve interposed between said air supplying means and said cylinder, said valve comprising a main valve chamber, an inlet duct communicating with one end portion of said main valve chamber, an auxiliary chamber, a passage communicating intermediately with said main chamber and connected with said cylinder, a slide valve movable in said main chamber to connect said passage with said inlet duct or to cut it off therefrom, one end of said slide valve being exposed to the pressure at said inlet duct, and means actuated by the admission of compressed air to said auxiliary chamber for moving said slide valve to connect said passage with said inlet duct.

3. In an operating mechanism for dump cars, the combination with means for supplying compressed air, and an operating cylinder, of a valve interposed between said air supplying means and said cylinder, said valve comprising a main valve chamber, an inlet duct communicating laterally therewith, an auxiliary chamber, a passage communicating with said main chamber and connected with said cylinder, a slide valve movable in said main chamber to connect said passage with said inlet duct, said main valve chamber also communicating with said inlet beyond the end of said slide valve, and means actuated by the admission of compressed air to said auxiliary chamber for

operating said slide valve to admit air to said cylinder.

4. A valve comprising a main valve chamber, an inlet duct leading to one end portion thereof, an auxiliary chamber communicating with the opposite end of said main chamber, a passage communicating intermediately with said main chamber, an exhaust port leading from said main chamber into said auxiliary chamber, a second exhaust port leading out of said auxiliary chamber, a valve movable in said main chamber to connect said passage either with said inlet duct or with said first mentioned exhaust port, and means actuated by the admission of compressed air to said auxiliary chamber for moving said valve to connect said inlet with said passage.

5. A valve comprising a main valve chamber, an inlet duct leading to one end portion thereof, an auxiliary chamber communicating with the opposite end of said main chamber, a passage communicating intermediately with said main chamber, an exhaust port leading from said main chamber into said auxiliary chamber, a second exhaust port leading out of said auxiliary chamber, a valve movable in said main chamber to connect said passage either with said inlet duct or with said first mentioned exhaust port, an inlet duct leading to said auxiliary chamber, and a piston in said auxiliary chamber between the latter inlet and said second exhaust port for reciprocating said valve.

6. A valve comprising a main valve chamber, an inlet duct leading to one end portion thereof, an auxiliary chamber communicating with the opposite end of said main chamber, a passage communicating intermediately with said main chamber, an exhaust port leading from said main chamber into said auxiliary chamber, a second exhaust port leading out of said auxiliary chamber, a valve movable in said main chamber to connect said passage either with said inlet duct or with said first mentioned exhaust port, an inlet duct leading to said auxiliary chamber, a piston in said auxiliary chamber between the latter inlet and said second port for reciprocating said valve, and a spring in said auxiliary chamber tending to move said piston in one direction.

7. In an operating mechanism for dump cars, the combination with a compressed air reservoir, a train pipe, and an operating cylinder, of a valve comprising main and auxiliary chambers, means connecting one end portion of said main chamber with said reservoir, means connecting said auxiliary chamber with said train pipe, means connecting the intermediate portion of said main chamber with said cylinder, means in said main chamber normally operating to cut off the flow of air from said reser-

voir through said main chamber to said cylinder and actuated by the admission of compressed air from said train pipe to said auxiliary chamber to admit air from said reservoir to said cylinder, and means for controlling the admission of air from said train pipe to said auxiliary chamber.

8. In an operating mechanism for dump cars, the combination with a compressed air reservoir, a train pipe, and an operating cylinder, of a valve comprising main and auxiliary chambers, means connecting one end portion of said main chamber with said reservoir, means connecting said auxiliary chamber with said train pipe, means connecting the intermediate portion of said main chamber with said cylinder, means in said main chamber normally operating to cut off the flow of air from said reservoir through said main chamber to said cylinder and actuated by the admission of compressed air from said train pipe to said auxiliary chamber to admit air from said reservoir to said cylinder, means for controlling the admission of air from said train pipe to said auxiliary chamber, a piston in said cylinder, a cut-off valve between said reservoir and said main chamber, and means for actuating said cut-off valve when said piston approaches the limit of its operating stroke to cut off the admission of air from said reservoir to said main chamber.

9. In an operating mechanism for dump

cars, the combination with a compressed air reservoir, a train pipe, and an operating cylinder, of a valve comprising main and auxiliary chambers, means connecting one end portion of said main chamber with said reservoir, means connecting said auxiliary chamber with said train pipe, means connecting the intermediate portion of said main chamber with said cylinder, means in said main chamber normally operating to cut off the flow of air from said reservoir through said main chamber to said cylinder and actuated by the admission of compressed air from said train pipe to said auxiliary chamber to admit air from said reservoir to said cylinder, means for controlling the admission of air from said train pipe to said auxiliary chamber, a piston in said cylinder, a cut-off valve between said reservoir and said main chamber, and means for actuating said cut-off valve when said piston approaches the limit of its operating stroke to cut off the admission of air from said reservoir to said main chamber.

JAMES D. BENBOW.
